UNITED STATES PATENT OFFICE.

PETER MOQUIST, OF MINNEAPOLIS, MINNESOTA.

GAS BURNER.

Application filed January 30, 1922. Serial No. 532,625.

To all whom it may concern:

Be it known that I, PETER MOQUIST, a citizen of the United States, residing at Minneapolis, in the county of Hennepin and State of Minnesota, have invented certain new and useful Improvements in Gas Burners; and I do hereby declare the following to be a full, clear, and exact description of the invention, such as will enable others skilled in the art to which it appertains to make and use the same.

This invention relates to a gas burner of the type commonly used in stoves or furnaces. In burners as heretofore constructed, the flames do not entirely consume the fuel but are cooled below the combustion temperature before complete combustion takes place.

It is an object of this invention to so construct the burner that the flames will be controlled and so confined and directed that a complete combustion of the gas will be obtained.

It is a further object of the invention to provide a mixing chamber having means for conducting air and gas thereto and equipped with fuel or flame apertures, together with means for directing additional air thereto, the chamber being so constructed that this additional air will be heated before reaching the place of ignition.

It is a further object to provide such a mixing chamber comprising a plurality of radially extending arms having a flaring formation both outwardly and upwardly and to provide regulatable means for directing air upwardly between said arms.

These and other objects and advantages of the invention will fully appear from the following description made in connection with the accompanying drawings in which like reference characters refer to the same parts throughout the different views and in which,

Fig. 1 is a view partly in front elevation and partly in central section of the burner;

Fig. 2 is a horizontal section taken on the line 2—2 of Fig. 1;

Fig. 3 is a plan view of the burner with the upper part of the wall being removed and a portion of the top of the mixing chamber being broken away; and

Fig. 4 is a top plan view of the burner.

Referring to the drawings, a gas supply pipe 1 is shown having therein a turn-on

or controlling valve 2, the end of the pipe 1 extending upwardly and being provided with the usual contracted tip or nozzle. The tube 3 extends a short distance below the tip or nozzle surrounds the same, and is provided with inwardly extending arms connected thereto and to a hub 4 firmly secured in any suitable manner to the pipe 1 and forming a support for said tube 3, as well as for the burner parts attached thereto. The tube 3 extends upwardly some distance from the end of pipe 1 and has its exterior diameter somewhat reduced adjacent its upper end to form a shoulder on which is seated a plate 5 having a central annular portion from which extend sector-like arms provided at their outer ends with upturned semi-cylindrical flanges 5^a. A member 6 formed as a short cylindrical member is disposed about the bar 3, spaced on and intermediately above the plate 5 and has a bottom portion therein through which are formed a plurality of openings 6^a of sector-like shape. These openings correspond in numbers to the arms of the members 5. The member 6 is adapted to be turned so that the openings 6^a extend more or less over the arms of the member 5 to regulate the amount of air which can pass upwardly through said openings. The member 6 is provided at its lower portion with downwardly extending lugs 6^b adjacent the sides of the opening therein which form stop members adapted to contact the arms of the member 5 and determine the position of the member 6 when the openings 6^a are entirely covered, as shown in Fig. 2.

Secured to the upper portion of the tube 3 is a member 7 having a plurality of radially extending arms, each of which has an outwardly, as well as an upwardly flaring formation. The member 7 is of comparatively short height and is closed at the bottom except for the open receiving tube 3. A plate 8 shaped to fit over the top of member 7 extends thereover, forms a cover therefor and has depending tongues at its outer edges disposed centrally of the arms of said member which fit into recesses 7^a formed in the top edges of said arms which prevent rotation of the member 8. The sides of the arms of the member 7 are formed along their top edges with a plurality of V-shaped grooves 7^b and a similar groove is also formed through the edge of the member 7 substan-

tially midway between the arms thereof, and a plurality of holes 7^c are also formed through the member 8 disposed circumferentially with the center thereof and over 5 the pipe or tube 3. The member 5 is formed at the top edge of and centrally of its upwardly extending arms with lugs 5^b and the lower section of a hood or combustion chamber casing 9 is provided with corresponding 10 recesses fitting over said lugs, the member 9 resting upon and being supported by the up- standing flanges 5^a of the member 5. The member 9 is of rounded and upwardly 15 curved shape and is provided in its upper edge with a plurality of curved recesses adapted to receive similarly shaped lugs 10^a of a top casing 10 shaped to fit upon and be supported by the upper edge of the cas- 20 ing 9 and which is provided with a flat top portion having therein a plurality of aper- 25 tures 10^b. The said top portion is also formed on its exterior surface with a cross- shaped rib 11.

The operation of the burner is as follows. 30 The gas will be supplied through the pipe 1 and will pass upwardly through the tube 3. A certain amount of air is also drawn up through the bottom of the tube 3 and will mix with the gas, and the mixture will pass 35 into the chamber 7 and will issue through the openings formed by the notches 7^b and the cover 8 as well as through the opening formed centrally between the arms. These 40 openings or passages are so directed that they will intersect or converge along the line ex- tending substantially centrally between the 45 arms of member 7 and substantially in aline- ment with the axis of the opening between said arms. Air will also be admitted 50 through the opening 6^a and the member 6, the amount of this air being regulated by turning the member 6 on member 5. The 55 space between the arms of member 5 is dis- posed directly under the arms of member 7 so that the air will be directed upwardly 60 against the arms of member 7. The fuel mixture emerging through the openings 7^b will be ignited and the flames being directed as stated by said openings, will then focus 65 along the line extending centrally between said arms. The sides of the arms of member 7 will be heated and as the air rises therebetween it will contact with the outwardly flaring walls of these arms and be heated there- 70 by. This air will mix with the fuel mixture issuing from the openings in said arms and the flame will extend upwardly in the com- 75 bustion chamber formed by casings 9 and 10 and issue from the openings in the top of the casing 10. Some of the mixture in member 80 7 will also issue through the hole 7^c and flames will form projecting upwardly from these openings. The burning mixture is confined in the casings 9 and 10 and the flames will be maintained at sufficient tem-

perature to complete burning all of the com- 70 bustible mixture. With this construction, therefore, the flames are converged at their initial ignition point and a high and concen- 75 trated zone of temperature is produced and a high degree of temperature is also main- tained in the combustion chamber. The flames are thus not allowed to become cooled off by contact with cold air surrounding the same and the combustible material cannot escape unburned. The amount of air required for the amount of fuel can be varied to suit the quantity and pressure of the latter so that a very efficient combustion can at all 80 times be maintained.

While the burner is shown as supported from the pipe 1, it may, of course, be sup- 85 ported by a surrounding grid or grate, if de- sired. This structure depends upon the use to which the burner is put.

From the above description it is seen that applicant has provided a simple and efficient form of gas burner and one which can be used to maintain an efficient combustion of the fuel under various degrees of pressure of 90 the gas. The parts of the burner are easily made and the same is easily and quickly as- 95 sembed.

It will, of course, be understood that vari- 95 ous changes may be made in the form, de- 100 tails and arrangement of the parts without departing from the scope of applicant's invention, which, generally stated, consists in the matter shown and described and set forth in the appended claims.

What is claimed is:

1. A burner comprising a mixing cham- 105 ber having a plurality of spaced arms, each upwardly flaring in cross section and having laterally directed openings in the sides 110 thereof, means for directing air upwardly between said arms whereby the air will strike the flaring sides thereof and be heated as it rises.

2. A burner comprising a mixing cham- 110 ber having a plurality of radially extending outwardly flaring arms, said arms also flaring upwardly and each having a plu- 115 rality of laterally directed apertures ad- jacent the upper edge thereof forming flame nozzles, means for conducting air and gas into the interior of said chamber, and means for conducting a determined amount of air into the space between the arms of said chamber.

3. The structure set forth in claim 2, and a hood having a combustion chamber surrounding and extending above said mix- 120 ing chamber and provided with plurality of openings in the top thereof.

4. A burner having a mixing chamber formed with a plurality of radially extend- 125 ing outwardly flaring arms, each having a plurality of laterally directed openings in the sides thereof, means for directing air 130

and gas into said chamber, and means for directing air upwardly between the sides of said arms.

5. A burner having a mixing chamber comprising a comparatively flat chamber having radially extending arms, a central opening in the bottom of said chamber, an air and gas inlet tube opening thereinto, a plate shaped similarly to said chamber and 10 covering the same, notches formed at the top of each side of each of said arms forming with said plate fuel passages, said passages directed along lines extending centrally between said arms.

15 6. A burner comprising a mixing chamber having radially extending outwardly flaring arms, each of said arms having a plurality of laterally directed openings therethrough forming fuel passages and 20 flame nozzles, said passages being directed to converge along a line extending centrally between said arms, means for conducting air and fuel into the said chamber, and means for directing a determined amount of air 25 upwardly between said arms.

7. The structure set forth in claim 6, said chamber also having an outwardly directed

opening therethrough disposed substantially centrally between said arms.

8. The structure set forth in claim 6, said 30 chamber also having a plurality of circumferentially arranged holes through the top thereof.

9. A burner comprising a base supply pipe, a tube supported from said pipe surrounding the same at its lower end and extending upwardly therefrom, a plate having sector shaped arms secured adjacent the upper end of said tube, a short cylindrical member having sector shaped openings through its lower side rotatably mounted upon said plate, a mixing chamber having radially extending outwardly flaring arms supported at the upper end of said tube, the arms thereof being disposed over 45 the spaces between the arms of said plate, and a closed substantially cylindrical chamber supported upon said plate surrounding said mixing chamber and extending thereabove and having a plurality of openings 50 through its top portion.

In testimony whereof I affix my signature.

PETER MOQUIST.
